INVENTOR:

Samuel D. Robinson

UNITED STATES PATENT OFFICE.

SAMUEL D. ROBINSON, OF FOXBOROUGH, MASSACHUSETTS.

HAT.

SPECIFICATION forming part of Letters Patent No. 255,674, dated March 28, 1882.

Application filed February 11, 1882. (Model.)

To all whom it may concern:

Be it known that I, SAMUEL D. ROBINSON, of Foxborough, in the county of Norfolk, in the State of Massachusetts, have invented certain Improvements in Hats for Ladies' and Children's Wear, of which the following is a specification.

Heretofore hats and other head-coverings for ladies and children have been made of cotton fabric, known as "canton-flannel," and also of felt having a covering of flocks which are made to adhere to the felt, the object being to produce a downy or fleecy appearance. The nap produced upon the surface of the cotton fabric has, however, little elasticity, and soon becomes laid or matted, especially if it becomes wet or is much handled, and the fleecy appearance sought for is soon destroyed. A variety of dye-stuffs and other coloring-matter used in these goods increases this tendency.

My invention consists of a hat or other head-covering for ladies and children, composed of a mixed fabric of cotton and wool, having a napped or fleecy surface, the wool being so incorporated in the fabric that fibers of the wool will be brought into and constitute a part of the nap in the process of raising the same. The fibers of wool have a much greater elasticity than those of cotton, and this quality of the wool serves to sustain the bed of fleece on the surface and keep it light and downy. The staple of wool being considerably longer than that of ordinary cotton, very rich and beautiful effects can easily be produced by combining cotton and wool of different colors, the cotton furnishing the ground-color, and the longer-stapled wool, in properly-contrasted colors, overlying the ground. It will be observed that owing to the greater length of the wool-staple the surface will consist wholly or chiefly of wool. It is well known that wool is capable of brighter and fresher effects in colors than cotton; and hence I obtain a superior luster in these hats of my invention. Among other things, I am able hereby to produce close resemblances to furs much in use—as those of the otter, seal, and beaver. I find it sufficient to incorporate the wool with the filling only of the fabric, the warp being wholly of cotton. Twenty per cent. of wool in the filling, the balance being cotton, is sufficient to produce a very good result, although the proportions may vary indefinitely, according

to taste or particular effect desired. Some other materials, with a comparatively long staple—as silk and some kinds of grasses—can be employed in combination with cotton as a substitute for wool or in connection with the wool.

In making my new hat I prefer to raise a nap on only one side of the cloth, and then to cement or otherwise fasten two pieces together with the nap-surfaces exposed, and then press the material into the shape desired. The nap or pile is then carded or combed up into a light fleece. It is obvious, however, that a hat may be made in substantially the same way from a single thickness of the fabric to form the upper surface of the hat, the place of the under layer being supplied by a plain fabric, with or without an ornamental lining; or a single thickness of the napped fabric may be used with any other proper support to sustain the brim and other parts in the desired form.

In the accompanying drawings, forming a part hereof, Figure 1 is a view of my invention complete. Fig. 2 is a view of a piece of the material of which the hat is composed, being the same hereinbefore described. Fig. 3 is a section after the two pieces are combined, showing a sectional edge.

I do not claim broadly a hat composed of two pieces of napped fabric fastened together; but

What I do claim, and desire to secure by Letters Patent, is—

1. As a new article of manufacture, a hat or other head-covering for ladies and children, made of cloth composed in part of cotton and in part of wool, the latter having a longer staple than the cotton, a nap or pile being raised upon the surface of said cloth of substantially the composition herein described.

2. A hat or other head-covering for ladies and children, composed of two pieces of cloth of the kind described, fastened together with the nap or face side exposed.

3. A hat for the purposes specified, composed of the cloth described, having a nap upon its upper surface of the composition described, and an under lining of silk or other ornamental character.

Witnesses: SAMUEL D. ROBINSON,
ERASTUS C. ALDEN,
CHARLES W. GREENE.
